UNITED STATES PATENT OFFICE.

ANNA DAVEY, OF CARTHAGE, MISSOURI.

DETACHABLE WINDOW-PANE FOR FLEXIBLE CURTAINS.

1,245,573.

Specification of Letters Patent.

Patented Nov. 6, 1917.

Application filed November 13, 1916. Serial No. 131,124.

To all whom it may concern:

Be it known that I, ANNA DAVEY, a citizen of the United States, residing at Carthage, county of Jasper, and State of Missouri, have invented certain new and useful improvements in Detachable Window-Panes for Flexible Curtains, of which the following is a specification.

This invention relates to panes such as are used in flexible curtains, particularly on automobile and other vehicles where a light or window is required in a curtain, hood, top, or the like.

Panes of this character are usually of a flexible and fragile material and very liable to breakage, requiring renewal from time to time, if dangerous drafts are to be prevented when touring. Renewal, when the pane is a permanent part of the curtain, hood, or top, usually necessitates special repairs at considerable expense and delay.

My object is to provide an improved removable pane or "light" for flexible curtains, hoods, tops and at other situations where this character of pane is employed which may be readily removed, when damaged, and another pane quickly and easily substituted therefor without necessitating special repairs, delays, or expense other than the minimum cost of a substitute pane.

Another object of the invention is the provision of novel means, or a holder, on the flexible curtain, hood, top or other device for holding a removable pane in such manner that danger of breakage thereof, is minimized and the pane is securely held and rendered adaptable for quick and easy removal, when damaged, for the substitution of a perfect pane. In my invention the holder into and out of which the light or pane is slidable, and an improved arrangement of protecting and retaining strips disposed on opposite sides of the pane and arranged cross-wise thereof, constitute the means for holding the pane in position and, in addition, there is provided an entrance portion, detachably closed by fasteners, preferably those of the snap button type through which the pane is slid when inserting it in

the holder, or, when removing it therefrom. The retaining portion of the holder is preferably composed of permanently connected plies, the snap buttons or fasteners and the entrance portion serving to retain the pane in said holder. With this construction I obviate the necessity of providing fasteners

passing through the edges of the pane for directly connecting it to the curtain, hood, top, or the like as has been previously proposed in constructions employing detachable panes. The expense of manufacture and difficulty of manipulation in inserting or removing a pane, incident to earlier devices is thereby obviated.

The invention is susceptible of modification and consequently the disclosure thereof which is hereinafter given should be considered as illustrative, rather than restrictive, of the scope of the invention.

In the accompanying drawings:

Figures 1 and 2 are opposite elevations, the ply being turned back at the entrance, Fig. 2;

Fig. 3, a face view of the pane, and

Fig. 4 an enlarged section on line 4—4 of Fig. 2.

A portion of a vehicle or automobile hood, curtain, or top is designated in the drawings at 1, as having the opening 2. Surrounding the opening there may be a facing 3, on the inside of the curtain 1 but this is not essential. Reinforcing the opening on the outside of the curtain 1 is a strip or ply 4.

A strip or ply 5 surrounds the opening on the inside of the curtain and is stitched at 6, said ply being otherwise free and constituting, in connection the material at the rear of the reinforcing ply 4, a holder for the reception of the pane or light 2^a. One portion, preferably at one end of the opening in the curtain, is left open as at 7 to a sufficient extent to admit the end of the pane when being slid into the holder or to enable the pane to be withdrawn therefrom. A lining 8 may be provided for the ply 5. Fasteners 9 whose mating parts are carried by the loose portion 7 and by the curtain 1 constitute a means to close the entrance portion of the holder and to retain the pane in position. Preferably, snap fasteners are employed which are concealed when the holder is closed.

Arranged to lie on opposite sides of the pane or light 2^a are retaining and protecting strips or braces 10 and 11. Preferably these strips or braces are, in each instance, crossed and stitched together at their crossed portions 12. The ends of the strips or braces may be anchored or fastened to the plies 4 and 5 in any desired manner but to provide a neat appearance the ends of the

strips or braces may be entered, in one instance, between the facing 3 and the opposite ply 4 and, in the other instance, between the facing 8 and the ply 5.

5 Having thus described my invention what I claim as new, and desire to secure by Letters Patent, is:

1. A pane holder for flexible curtains and the like comprising continuous, freely related, connected plies which are separated at one portion, thereby providing a pane entrance, releasable means for closing said entrance, a removable pane adapted for insertion through said entrance, whose edge 10 lies between and is held by said plies inside the points where the plies are connected to-

gether, and means connected to the plies and overlying the pane for preventing the pane from becoming detached from the plies.

2. The combination with a flexible curtain or the like having a pane holder comprising plies, of a removable pane whose edge is received between and held by said plies, said plies having a pane entrance, releasable means for closing said entrance, 25 and protectors disposed on opposite sides of the pane which are connected to the respective plies aforesaid.

In testimony whereof, I hereunto affix my signature.

MRS. ANNA DAVEY.
